UNITED STATES PATENT OFFICE.

GAVIN SHEARER HAMILTON, OF MOTHERWELL, AND THOMAS THOMSON, OF HOLYTOWN, SCOTLAND.

AXLE MILL.

Application filed February 15, 1922. Serial No. 536,664.

To all whom it may concern:

Be it known that we, GAVIN SHEARER HAMILTON and THOMAS THOMSON, subjects of the King of the United Kingdom of 5 Great Britain and Ireland, and residing, respectively, at Motherwell, Scotland, and Holytown, Scotland, have invented a certain new and useful Improvement in Axle Mills, of which the following is a specification.

This invention relates to axle mills of the type comprising superposed relatively reciprocating plates of which the adjacent faces are spaced to accommodate the bar to 15 be treated and are shaped to conform with the contour of the finished axle, and means for imparting pressure to said plates, the arrangement being such that the bar is constrained to rotate between the plates and is 20 pressed and rolled to the desired configuration.

The present invention is characterized primarily by the feature that the plates are divided into three sets of which the intermediate set is first brought into operation to 25 form the middle portion of the axle whereupon the external sets are brought into operation to form the ends of the axle.

A further feature consists in the provision 30 of means for imparting feeding movements concomitantly to the upper and lower external sets of plates such means comprising power operated screw-and-nut feeding mechanism for the upper external sets and feeding wedges interconnected therewith for the lower external sets.

In the drawings which illustrate the invention Fig. 1 is an end elevation, Fig. 2 a side elevation and Fig. 3 a plan.

The axle mill shown comprises three sets 40 of plates 1, 1^a, 2, 2^a, 3, 3^a in superimposed relation and guided in a frame 4 to perform rectilinear reciprocating movements in opposite directions.

The plates 1, 2 and 3 are connected to 45 move simultaneously lengthwise by lugs 30, 31 projecting inwardly from the plates 2, 3 into engagement with vertically disposed slots 32, 33 in the plate 1, the arrangement 50 being such that the plates 2, 3 are free to move vertically of the plate 1. Similarly, the plates 1^a, 2^a and 3^a are connected to move simultaneously lengthwise, the plates 2^a, 3^a being formed with lugs 30^a, 31^a and the plate 55 1^a being formed with slots 32^a, 33^a corre-

sponding in function to the lugs 30, 31 and slots 32, 33.

The plates 2, 3 are provided with eyes 34, 35 and the plates 2^a, 3^a are provided with eyes 34^a, 35^a connected respectively to rods, 36, 37, 38, 39 which, in turn are connected at 60 36^a, 37^a, 38^a and 39^a to levers 40, 41 rigidly secured to a rock-shaft 42 journaled in pedestals 43, 44. Connected to the levers 40, 41 are rods 45, 46 which are constrained to 65 reciprocate by any convenient source of power. The rods 45, 46 are caused to reciprocate continuously so that the plates 1, 2 and 3 reciprocate continuously and the plates 1^a, 2^a and 3^a reciprocate continuously 70 in the directions opposite to those of the plates 1, 2 and 3.

The adjacent faces of the sets of plates are spaced to accommodate the iron or steel bar 5 and are shaped to conform with the 75 contour of the finished axle. Means herein-after described are provided for imparting feeding movements to the intermediate set to form the middle portion of the axle and then for imparting feeding movements to 80 the external sets to form the ends of the axle. It will be seen that the bar 5 is constrained to rotate between the plates and is 85 pressed and rolled to the desired configuration.

In the operation of the mill, the intermediate set 1, 1^a is first moved vertically and thus brought into operation to form the middle portion of the axle, sets 2, 2^a and 3, 3^a, meanwhile reciprocating idly then the 90 external sets 2, 2^a, 3, 3^a which are preferably interconnected are moved vertically and thus brought into operation to form the ends of the axle.

The plate 1^a is immovable vertically and the plate 1 is adapted to be fed towards the bar 5 to form the middle portion of the axle by means of screws 6 in screw-threaded engagement with a fixed bar 7 and pressing on the guide 8 for the plate 1, the screws being simultaneously rotatable by motor driven worms 9 and worm wheels 10.

For imparting feeding movements concomitantly to the upper and lower external sets of plates 2, 2^a, 3, 3^a whereby to form the ends of the axle there are provided screws 11 engaging the bar 7 and pressing the guides 12 for the plates 2, 3, and connected motor driven worms 13 engaging worm wheels 13^a secured to the screws 11, the sets 110

2^a, 3^a being fed by wedges 14 acting as guides for the plates 2^a, 3^a and operated by rack-and-pinion mechanism 16 interconnected by means of shafts 17 and bevel gears 18 with 5 the worms 13.

To reduce friction, rollers 19 are inserted between the several guides and the relative plates whereby to form a roller track.

It will be seen that, due to division of the 10 plates into sets only certain parts of the length of the bar need be compressed at any time during the rolling process, the parts of the bar being thus allowed to swell or lengthen as required according to the work 15 being done on the centre or on the journal portions of the bar.

I claim:-

1. An axle mill comprising, in combination, three sets of superposed plates mounted 20 for relative reciprocatory movement and presenting operative faces spaced to accommodate the bar to be treated and shaped to conform with the contour of the finished axle and means for first imparting feeding 25 movements to the intermediate set of the three to form the middle portion of the axle

and then imparting feeding movements to the external sets of the three to form the ends of the axle.

2. An axle mill comprising, in combination, three sets of relatively reciprocatory upper and lower plates presenting operative faces spaced to accommodate the bar to be treated and shaped to conform with the contour of the finished axle, means for imparting feeding movements firstly to the intermediate set of the three so as to form the middle portion of the axle, and means for imparting feeding movements secondly to the external sets of the three so as to form 40 the ends of the axle, said last named means comprising screw-and-nut mechanisms for feeding the upper sets and wedges for feeding the lower sets.

In testimony whereof we have signed our 45 names to this specification in the presence of two subscribing witnesses.

GAVIN SHEARER HAMILTON.
THOMAS THOMSON.
